10 Claims. (Cl. 66—110)

1

The present invention relates to Cotton knitting machines and more particularly to a method and apparatus permitting to obtain two paths of different lengths for the slurcocks and the driving heads of the thread guides on a Cotton knitting machine, in which the angular extent of motion of the operating lever is varied by means of a sliding block which is arranged in a guide slot provided in the operating lever, the essential feature of the invention consisting in this that the displacement of the sliding block from one position to the other is derived from the movement of the Coulier mechanism itself in such a way that the change in length of the path of the slurcocks and of the driving heads for the thread guides, and also the exchange of the driving heads take place during the period of sinking a single course of loops.

In the knitting of narrowed hosiery by means of Cotton knitting machines hitherto in use the slurcocks and the driving heads of the thread guides are moving in the majority of cases over the whole width of the needle row although the width of the product gradually diminishes due to the narrowing in the calf portion. More particularly from the beginning of the high heel to the termination of the toe the width of the product is reduced, and with a constant path of the slurcocks and of the driving heads for the thread guides it is the usual practice to reduce the number of revolutions of the machine, whereby considerable losses of time arise.

Methods have been devised for reducing the time losses by controlling the length of the slurcock paths. In accordance with one of the methods hitherto known the angular extent of movement of the operating lever is varied by means of a block slidably mounted in a guide slot provided in said lever. In accordance with another method the reverse arrangement is used, the block being rigidly connected to the rocking lever and the guide slot being movable on the block. The movement of the block, or of the guide slot, is derived either from a control linkage actuated by hand or mechanically, or from the narrowing mechanism itself.

The use of a control linkage has not proved successful because it is difficult to shift the same by hand during the operation of the machine. A connection provided between the control linkage and the narrowing mechanism would permit, in view of the pitch of the spindle threads, a gradual variation only in the length of the slurcock paths over a time longer than that during which the slurcocks effect the sinking of a course

2

of loops so that such an arrangement cannot be used as an universal means for the simultaneous control of the slurcocks and of thread guide driving heads and also for effecting the thread guide exchange from the range of the shortened paths of the slurcocks and driving heads.

In order to eliminate the above imperfections, the present invention provides for performing the movement of the slurcocks and guide thread driving heads along two paths of different lengths and for exchanging the thread guides from the range of the shortened paths of the slurcocks and driving heads by means of the Coulier mechanism, the exchange of the paths of different length for the slurcocks and thread guide driving heads being derived from the movement of the Coulier mechanism itself during the period of sinking a course of loops by the slurcocks.

The method of the present invention may be used with advantage to increase the output of a Cotton knitting machine, more particularly a machine of fine division or pitch, in which a far more sensitive yarn is used since with a narrowed path of the slurcocks and thread guide driving heads the number of revolutions of the main cam shaft may remain constant, as with a shortened path of the slurcocks the desired reduction in the sinking speed of the slurcocks and thread guide driving heads takes place in accordance with the formula

$$c = \frac{s}{t}$$

where c represents the sinking speed of the slurcock and thread guide driving head, s the path of the slurcock and t the time taken by the slurcock to travel over the path s . The jack sinkers then move at a slower speed between the knitting needles, and also the thread guides lay the yarn at a slower rate. Thereby the stress on the yarn is considerably reduced and during the period of knitting the high heel, instep and toe a clean plating is obtained as well as a more reliable operation of the thread guides. The movements following the formation of a loop course are performed at normal speed corresponding to the constant speed of the cam shaft.

The method of the invention is of great importance also in connection with the exchange of the thread guides, for instance, after the knitting of the heel pieces has been terminated, when the strengthening thread guide working in the range of the shortened slurcock path is to be brought to the edge of the needle row into inoperative position and to be replaced by a

new thread guide for knitting the instep before the next shortened path of the slurcocks begins.

A constructional embodiment of the invention is shown by way of example in the accompanying drawings, in which

Fig. 1 is an elevation of the Coulier and change-over mechanism shown in the extreme left hand position of the operating lever;

Fig. 2 is a section along the line II—II of Fig. 1;

Fig. 3 is a section along the line III—III of Fig. 1;

Fig. 4 is a section along the line IV—IV of Fig. 1;

Fig. 5 is a section along the line V—V of Fig. 1;

Fig. 6 shows a detail of the safety member for securing the positions of the sliding members;

Fig. 7 shows an example of narrowing when knitting a lady's stocking on a Cotton knitting machine, the positions of the thread guides being also shown;

Fig. 8 is an enlarged fragmentary perspective view illustrating the details of the switch bar, rack and safety device forming part of the change-over mechanism.

During the period of knitting the welt and leg portion of the stocking shown in Fig. 7 the length of the path of the slurcocks and driving heads for the thread guides is approximately 500 millimeters corresponding to the working width A, the said length being reduced within the section C of the stocking, i. e. from the edge of the welt to the second main narrowed part of the stocking, to about 350 millimeters in the section D of the stocking so as to correspond to the working width B. If, for instance, a standard lady's stocking of 45 gage consists as a whole of 2000 courses, the slurcocks and driving heads for the thread guides work during a period corresponding to about 1200 courses over a width A and a length C and during the remaining 800 courses over a width B and a length D, whereby with a constant number of revolutions of the main cam shaft an economy of more than 20% of the working time necessary for knitting a complete stocking is secured.

The main Coulier cam 1 is rotated in a manner known per se from the main cam shaft 2 through the intermediary of the gears 3, 4 having a gear ratio of 1 to 2 (Fig. 3). One revolution of the Coulier cam 1 corresponds to the period of knitting two courses of loops, or to two revolutions of the main cam shaft. The gear 4 is fastened to one end of a shaft 5 which is mounted rotatably in the frame 6 of the machine. The opposite end of the shaft 5 carries fast on the same the main Coulier cam 1. Guides 7 are fastened on the frame 6 of the machine and a slide 8 is mounted for horizontal movement in the said guides, so as to have a path of constant length corresponding to the constant stroke of the main Coulier cam 1 (Fig. 1). Holders 9 are fastened by means of screws 10 on the slide 8 symmetrically with respect to the center of the latter, as shown in Fig. 3. Each holder 9 carries a nonrotatable pin 11 on which a roller 12 is rotatably mounted so as to travel in contact with the circumference of the Coulier cam 1. The central part of the slide 8 is formed a vertical guide slot 13 in which a sliding block 14 works, the cylindrical pin 15 of the sliding block carrying a rotatably mounted block 16, which is adapted to slide in a vertical guide slot 17 formed in the operating lever 18 (Figs. 1 and 3). The single arm operating lever is mounted pivotally on a pin 19 secured in the frame 6 of the machine (Fig. 5). To the end of the operating lever 18 is fastened a gear sector 20 having its teeth

in permanent engagement with a pinion 21, which is mounted rotatably on a fixed pin 23 together with a gear 22. The gear 22 engages with a pinion 24 fast on the shaft 25 of a worm 26. The helical thread 27 of the worm 26 entrains by means of the small rollers 28 the body 29 of the slurcock which body is slidably mounted on the fixed guide bar 30 (Fig. 5).

The sliding block 14 is rigidly connected to the end of a rack 31 which has its teeth in permanent engagement with a pinion 32 (Figs. 1 and 4). The pinion 32 is fastened on the end of a pin 33, which is mounted rotatably in, and adapted to be entrained by, the slide 8. The other end of the pin 33 is formed as a pinion 34 which is in permanent engagement with a rack 35 mounted slidably in an angle member 36 provided at the lower edge of the slide 8 (Fig. 5). The rack 35 is retained in position in lateral and vertical directions by means of guides 37. The front faces of the rack 35 carry each a set screw 38 secured by means of a nut 39 (Figs. 1 and 4). In one of the longitudinal walls of the rack 35 is provided a longitudinal groove 40 crossed by two vertical grooves 41 (Figs. 4 and 8). In the longitudinal groove 40 is slidably mounted a switch bar 42 whose exposed longitudinal wall is provided with a ramp or abutment 43. Also the ends of the switch bar 42 carry each a small set screw 44 secured by a nut 45. On the left hand side of the angle member 36 the wall of the slide 8 is provided with a rectangular opening 46 (Figs. 1 and 8), adapted to receive the four-sided casing 47 of a holder 48, the casing being fastened on the slide 8 by means of screws (Fig. 8). The holder 48 is provided with an opening 49 adapted to act as a guide for the pin 50 of a safety member 51 (Figs. 6 and 8). The safety member is forkshaped, the central part of the same being provided with inclined abutment surfaces 52 and the end part 53 being of rectangular shape corresponding to the shape of the vertical grooves 41 in the rack 35. One end of a spring 54 is secured on the holder 48 by means of a small screw 55, the opposite free end of the spring exerting a suitable pressure against the pin 50 of the safety member 51 (Figs. 5 and 8). In the space underneath the slide 8 the frame 6 is provided with bearing brackets 56 which are screwed to the frame under the guides 7 and carry the rotatably mounted shaft 57 of the change-over mechanism (Figs. 1 and 4). On the inner sides of the brackets 56 the reduced portions of the shaft 57 carry rigidly mounted abutment discs 58. Each disc 58 is provided on its periphery with six teeth 59 having a uniform pitch (Fig. 2). The relative position of the two abutment discs is determined by the teeth 59 of one of the discs being displaced by one half of the pitch length with respect to the teeth of the other disc. Accordingly, the axis of any of the teeth 59 of one of the discs 58 coincides with the axis of the gap between two teeth of the other disc (Fig. 4). The abutment discs 58 are held in position each by means of a fixing plunger 60 guided in the wall of the respective bearing 56 and subjected to the pressure of a helical spring so as to engage in a corresponding notch formed in the disc 58 (Fig. 1).

On the right hand half of the shaft 57 is pinned a pinion 61 having inclined teeth which engage with a worm wheel 62 pinned on the end of the shaft 63 (Figs. 1 and 2). The shaft 63 is rotatable in bearings 64 and 65 which are screwed to the frame 6 of the machine. On the opposite end of the shaft 63 is pinned a ratchet wheel 66 (Fig. 2) which by means of a pawl mechanism, not

shown, receives a step by step movement from a control drum, not shown.

The apparatus so far described operates in the following manner.

During the normal knitting of a stocking with a working width A and length C (Fig. 7), when the paths of the slurcocks and of the driving heads for the thread guides are of maximum length, the interconnected sliding blocks 14 and 16 are in their lower extreme position shown in Fig. 1, so that the angle of swivel of the operating lever 18 has its maximum value and the length of travel of the horizontally moving slide 8 is equal to the constant stroke of the main Coulier cam 1.

In order to knit the stocking with a narrowed working width B and a length D, it is necessary to shorten the paths of the slurcocks and of the driving heads for the thread guides, and also to shift the blocks 14 and 16 to their upper end position. For reducing the length of travel of the slurcocks and driving heads for the thread guides it is of advantage to keep the slurcock idle for a certain period upon completion of the sinking operation. This is achieved by the main Coulier cam 1, which is still normally rotating, by arranging the same in such a way that within a certain range of degrees its circumference does not act upon the rollers 12 of the slide 8, which occupies either its right hand or its left hand end position (Fig. 1). Together with the slide 8 the operating lever 18 occupies either its right hand or its left hand end position (Fig. 1). As it may be seen in Figures 2 and 4, the right hand abutment disc 58 is in such a position that a gap between its teeth 59 provides free passage for the rack 35 and switch bar 42 in their horizontal motion while a tooth 58 of the left hand abutment disc 58 lies in the path of these two members without exerting any influence on their operation. During the limited period of rest of the slurcock a control drum, not shown, gives rise to an impulse for turning the ratchet wheel 63, the turning being effected by a pawl mechanism, not shown. The rotation of the ratchet wheel 66 results in rotation of the shaft 63, worm gears 62 and 61, shaft 57 and of the two abutment discs 58 by one half of the pitch length of the teeth 59. In this way a tooth 59 of the right hand abutment disc 58 will be brought to a position in which it lies in the horizontal path of the rack 35 and switch bar 42. On the two abutment discs 58 being simultaneously rotated the curved periphery of the Coulier cam 1 begins to cooperate with the cam rollers 12 so that the slide 8 is moved to the right. Concurrently with the slide also the rack 35 and the switch bar 42 guided therein are entrained, so that the head of the set screw 44 is caused to abut against the front wall of a tooth 59 of the right hand disc 58. The switch bar 42 with the ramp 43 remains stationary while the rack 35 connected to the slide by means of the safety member 51 is carried further to the right. During the movement of the slide 8 to the right the inclined surfaces 52 of the safety member 51 are brought in contact with the stationary ramp 43 of the switch bar 42 whereby the rectangular end part 53 of the safety member 51 is disengaged from the left vertical groove 41 of the rack 35. During the further movement of the rack 35 in the original direction, the safety member 51 is constantly pushed aside by the ramp 43 until the head of the set screw 38 abuts against the same tooth 59 of the right hand disc. The movement of the rack 35 is thus arrested while the

slide 8 is still moving further to the right under the action of the Coulier cam 1. The pinion 34, which has been entrained by the slide 8 up to the moment when the rack 35 has been arrested, begins to roll along the teeth of the rack and thereby rotates about its own axis. Since the pinion 34 is rigidly connected to the pinion 32, the latter also rotates about its own axis and thereby carries upward the rack 31 and with the latter also the blocks 14 and 16 to their upper end position. This position is secured by engagement of the rectangular end part 53 of the safety member 51 in the right hand vertical groove 41 of the rack 35 due to the spring 54 acting on the pin 50 of the safety member 51.

By shifting the blocks to their upper end position during the time when the slurcock effects the sinking of a course of loops, the angle of swivel of the operating lever 18 is reduced while the length of travel of the blocks is not changed and the number of revolutions of the main cam shaft 2 and of the Coulier cam 1 remains constant. As the time remains unchanged and the path of the slurcocks and driving heads for the thread guides is shortened, the speed of the same is reduced.

The exchange of the original thread guide during the knitting of the narrow stocking length D with the width B for a new thread guide, which until then has remained inoperative in the end position E (Fig. 7), occurs with the aid of an end stop, not shown in the drawing, by two successive displacements of the blocks, that is, from the upper into the lower and back again into the upper end position, within the period of the looping of one row of stitches, in order that the driving head moving in one direction can bring the original thread guide from the operative position into the zone of the end stop, not shown in the drawing, that is, into the position E, and the new thread guide, during the subsequent return of the driving head, into the operative position on the narrowed width B. The opposite operation of the Coulier and change-over mechanism is the same as the above described operation, the only difference consisting in this that a tooth 59 of the left hand abutment disc 58 acts upon the set screws 44, 38 of the rack 35 and of the switch bar 42, which are entrained by the slide 8 in its movement to the left.

What I claim is:

1. In an apparatus for securing two paths of different lengths for the slurcocks and driving heads of the thread guides on a Cotton knitting machine, in which the angular extent of swivel of the operating lever is varied by means of a block slideable in a guide slot in the said lever, a Coulier mechanism for actuating said operating lever, and a transmission device actuated by the movement of the Coulier mechanism itself for effecting the sliding motion of the block in the guide slot from one position to the other whereby the change in the length of travel of the slurcocks and driving heads for the thread guides take place during the sinking of a course of loops.

2. In an apparatus for securing two paths of different lengths for the slurcocks and driving heads of the thread guides on a Cotton knitting machine, in which the angular extent of swivel of the operating lever is varied by means of a block slideable in a guide slot in the said lever, the provision of a reciprocating slide carrying a transmission device for controlling the shifting motion of the block in the guide slot of the operating lever.

3. In an apparatus for securing two paths of

different lengths for the slurcocks and guiding heads of the thread guides on a Cotton knitting machine, in which the angular extent of swivel of the operating lever is varied by means of a block slideable in a guide slot in the said lever, the provision of a reciprocating slide carrying a transmission device, which comprises a shifting rack mounted slidably on the slide and two interconnected pinions adapted to engage one with the shifting rack and the other with a second rack for displacing simultaneously two interconnected blocks, one in a guide slot provided in the slide and the other in the guide slot of the operating lever.

4. In an apparatus for securing two paths of different lengths for the slurcocks and driving heads of the thread guides on a Cotton knitting machine, in which the angular extent of swivel of the operating lever is varied by means of a block slideable in a guide slot in the said lever, the provision of a reciprocating slide carrying a transmission device, and a change-over mechanism adapted to be operated by a control drum so as to cause the block to be shifted in the guide slot of the operating lever.

5. In an apparatus for securing two paths of different lengths for the slurcocks and guiding heads of the thread guides on a Cotton knitting machine, in which the angular extent of swivel of the operating lever is varied by means of a block slideable in a guide slot in the said lever, the provision of a reciprocating slide carrying a transmission device, and a change-over mechanism adapted to be operated by a control drum so as to cause the block to be shifted in the guide slot of the sinker lever, the change-over mechanism being provided with abutment discs adjustable in the path of a shifting rack constituting a part of the transmission device carried by the reciprocating slide.

6. In an apparatus for securing two paths of different lengths for the slurcocks and driving heads of the thread guides on a Cotton knitting machine, in which the angular extent of swivel of the operating lever is varied by means of a block slideable in a guide slot in the said lever, the pro-

5 vision of a reciprocating slide carrying a transmission device, a change-over mechanism adapted to be operated by a control drum, and a safety member co-operating with the transmission device.

7. The apparatus as set forth in claim 6, in which the safety member is adapted to co-operate with the transmission device in such a way as to determine the end positions of a sliding block.

10 8. The apparatus as set forth in claim 6, in which the safety member is adapted to co-operate with the transmission device in such a way as to determine the end positions of two sliding blocks.

15 9. In an apparatus for securing two paths of different lengths for the slurcocks and driving heads of the thread guides on a Cotton knitting machine, in which the angular extent of swivel of the operating lever is varied by means of a block slideable in a guide slot in the said lever the provision of a reciprocating slide carrying a transmission device having a shifting rack mounted slidably on the slide, a change-over mechanism adapted to be operated by a control drum, a safety member co-operating with the transmission device, and a detent on the reciprocating slide adapted to engage in grooves which are provided in the shifting rack and correspond to the end positions of the sliding block.

20 10. The apparatus as set forth in claim 9, in which the detent is controlled by a switch bar mounted slidably in the shifting rack.
